UNITED STATES PATENT OFFICE.

KRAFT BOOTH, OF PHILADELPHIA, PENNSYLVANIA, ASSIGNOR TO GILLINDER & SONS,
INC., A CORPORATION OF PENNSYLVANIA.

DESIGN FOR A GLASS DOME FOR CEILING-LIGHTS.

45,146.

Specification for Design.

Patented Jan. 13, 1914.

Application filed August 8, 1913. Serial No. 783,823. Term of patent 7 years.

To all whom it may concern:

Be it known that I, KRAFT BOOTH, a citizen of the United States, residing in the city and county of Philadelphia, State of Pennsylvania, have invented a new, original, and ornamental Design for a Glass Dome for a Ceiling-Light, of which the following is a specification, reference being had to the accompanying drawing, forming part thereof.

Figure 1 is a perspective view of a glass dome for a ceiling light, showing my new design. Fig. 2 is a bottom plan outside view thereof.

1 designates the body of the dome, the

same being bowl-shaped and having on its exterior face the alternate convex shaped scallops 2, the facets 3 on the sides of said scallops, and field 4 above the upper terminals of said scallops, and the bead 5 at the top, said field and bead widening out from said upper terminals of the scallops.

I claim:—

The ornamental design for a glass dome for a ceiling light, as shown and described.

KRAFT BOOTH.
